United States Patent Office.

HARLOW C. SMITH, OF CHICAGO, ILLINOIS.

Letters Patent No. 66,050, dated June 25, 1867; antedated June 22, 1867.

IMPROVEMENT IN GRAIN-MEASURES.

The Schedule referred to in these Letters Patent and making part of the same.

TO ALL WHOM IT MAY CONCERN:

Be it known that I, HARLOW C. SMITH, of Chicago, in the county of Cook, and State of Illinois, have invented an improved Half-Bushel or Measure; and I do hereby declare that the following is a full, clear, and exact description of the same; reference being had to the accompanying drawings, and letters of reference marked thereon, making a part of this specification, in which—

Figure 1 is a perspective representation of my improved half-bushel.

Figure 2 is a top or plan view of my improved half-bushel.

Figure 3 is a vertical section taken through the centre of the half-bushel.

Figure 4 is a representation of the spring and spur that hold the bag to the rim of the half-bushel.

The object of my invention is to produce a measure to which the bag can be attached and the grain emptied by a hinged bottom of the measure into the bag, thus constituting a combined measure and bag-holder.

To accomplish this object I take a half-bushel, or other similar grain-measure, having its rim or body constructed in any of the ordinary methods. To this body C, I attach a bottom composed of two parts, A and B, as shown in figs. 1 and 3. The part A is attached rigidly to the body of the measure, and its upper surface is inclined at an angle of about twenty degrees, as represented in fig. 3. The part B is hinged to A so as to open downward, and is held shut when closed by means of the spring catch E, fig. 3. A ring, n, is secured to the upper surface of the lid or part B to pull it shut by after it has been opened to empty the grain. Upon the outside of the body C of the measure are secured three or more springs, D, as shown in fig. 1, there being a point, o, attached to the lower end of these springs, and projecting inward, as shown in fig. 4. A small recess is cut in the outside of the measure where these points are located, to permit the bag to be inserted under the springs, when it will be caught by the points and held attached to the measure.

The operation is as follows: The bag being attached to the measure, and the bottom being closed, the measure is filled with grain or other material to be measured. It is then lifted by the operator, who touches the upper end of the catch E, which unlocks the hinged portion of the bottom, which falls and lets the grain pass at once into the bag. The bottom is then shut by means of the ring n, or a string attached thereto, when the operation is repeated until the bag is full, when the measure is detached.

It will thus be seen that by means of my invention one person is enabled to perform the entire operation with ease and rapidity, thus dispensing with the services of a person usually required to hold the bag. If desired, the measure may be attached to any suitable support, and thus constitute a fixed bag-holder; but I intend it for use more especially as above described.

Having thus described my invention, what I claim, is—

A "half-bushel," or similar grain-measure for hand use, having its bottom composed of the stationary part A and the hinged portion B, and provided with the spring-hooks D, or their equivalents, for attaching the bag, all constructed and arranged to operate as shown and described.

HARLOW C. SMITH.
